TROWELING MACHINE

Wilfred W. Irwin, Dayton, Ohio, assignor to Master Vibrator Company, Dayton, Ohio, a corporation of Ohio

Filed Nov. 23, 1956, Ser. No. 624,162

2 Claims. (Cl. 94—45)

This invention relates to surfacing tools, and more particularly to a rotary power driven tool provided with sweep blades having a progressive circular wiping engagement over the surface upon which it operates, as for example an unset concrete surface.

In the embodiment of the invention in which it assumes the form of a concrete finishing tool, such tool comprises a generally upwardly extending handle by which an operator, while standing erect may move the tool about on the work surface. Also, in the concrete finishing embodiment of the apparatus the sweep blades are adjustable in order better to perform floating, finishing and intermediate operations.

The object of the invention is to simplify the construction as well as the means and mode of operation troweling machines, whereby such machines may not only be economically manufactured, but will be more efficient and satisfactory in use, adaptable to a wide variety of applications, and be unlikely to get out of repair.

It is a further object of the invention to enable the blades to be adjusted by the operator from a convenient position on the handle.

Another object of the invention is to provide for handle mounted adjustment of the sweep blades in conjunction with a telescoping type of handle as found in a troweling machine of the so-called midget or readily portable type.

A further object of the invention is to provide a generally new blade adjustment mechanism especially characterized by an ease of operation which precludes the necessity for relatively rigid and heavy controls. In this latter regard, a troweling machine comprises an engine, gear box and other mechanisms, the whole comprising a relatively heavy package which rests upon the sweep blades which in turn are directly in contact with the work surface. In adjusting the sweep blades in one direction, it is necessary according to conventional construction and arrangements of parts, bodily to lift the relatively heavy machine. The instant has in view a new structure providing for increased leverage of the adjustment forces acting upon the sweep blades and for increased flexibility in the sweep blades whereby the blades may more easily be tilted and whereby at least a part of the desired tilt is accomplished through a flexing of the sweep blades.

Still another object of the invention is to present a generally new mounting for the sweep blades providing for a different distribution of weight upon the sweep blades as well as for a different action thereof in operation and in response to tilting adjustments thereof.

A further object of the invention is to provide a troweling machine possessing the advantageous structural features, the inherent meritorious characteristics and the mode of operation herein mentioned.

With the above primary and other incidental objects in view as will more fully appear in the specification, the invention intended to be protected by Letters Patent consists of the features of construction, the parts and

combinations thereof, and the mode of operation as hereinafter described or illustrated in the accompanying drawings, or their equivalents.

Referring to the accompanying drawing wherein is shown one but obviously not necessarily the only form of embodiment of the invention,

Fig. 1 is a view in perspective of a concrete troweling machine in accordance with the illustrated embodiment of the invention;

Fig. 2 is a detail view, partly broken away, showing the lower part of the troweling machine and the train of mechanism comprised in the means for adjusting the sweep blades, including manipulative control means on the handle;

Fig. 3 is a view taken in the direction of the arrows in Fig. 2 and turned 90°.

Fig. 4 is a detail view, in plan, of a lever arm comprised in the sweep blade adjustment mechanism;

Fig. 5 is a view in side elevation of the arm of Fig. 4; Fig. 6 is a detail view, in plan, of a connector device or spider having a common connection with the several sweep blades for unison adjustment thereof.

Like parts are indicated by similar characters of reference throughout the several views.

Referring to the drawings, a concrete troweling machine in accordance with the instant invention comprises a power source 10 with its attendant devices, the whole being supported on a casting 11. The casting 11 is bolted in overlying superposed relation to a gear box 12 from the bottom of which extends a rotary drive shaft 13. The machine is supported in the generally upright position illustrated in Fig. 1, with the shaft 13 in a plane substantially normal to the surface of the work.

The tool is moved about over the surface of the work by a handle 14 pivotally connected to the gear box 12. As indicated, the present handle is of the telescoping kind, comprising a part 15 connected to the gear box and a part 16 slidable within the first part and held in a selected position of extension by a locking mechanism 17.

The rotary drive shaft 13 carries on its outer or lower end a mounting plate or base 18, the base being secured to the shaft 13 for unison rotation by means including a bolt 19 and a conventional key 21 as is shown in Fig. 2 of the drawings. The base plate 18 carries sweep blade assemblies 22 upon which the machine rests on the surface of the work and which are driven, as will be described, in a rotary direction about the shaft 13 for progressive wiping engagement with the surface of the work.

The power source 10 is effective to rotate a shaft 23 which is connected by pulleys 24 and 25 and a belt 26 with another shaft 27 extending into the gear box 12. It will be understood that, in the conventional manner of devices of the present class, the power source 10 is effective to rotate the shaft 23, and that the motion of such shaft is transmitted through the elements 24—26 and the elements of the gear box 12 to the rotary shaft 13, causing this shaft to rotate in correspondence with the shaft 23.

The base plate 18 is formed with a circumferential series of radial portions or spokes 28, each terminating in a boss in which is a bore or bearing mount 29 extending in a direction transverse to or substantially at right angles to the longitudinal axis of its respective spoke 28. The several bearing mounts 29 (in the present instance 3) may thus be said to lie in planes tangential to a common circle concentric with the shaft 13. Each bearing mount 29 receives a bolt 31 which may be suitably secured, as by a set screw 32, against rotary and longitudinal motion relatively to the base plate 18 within its respective mounting. On a projecting part of the

bolt 31 is rotatably mounted an attachment means or plate 33 including a bearing portion 34 on the bolt 31. From the bearing portion 34 the attachment member 33 extends in the form of a web 35 in a direction substantially parallel to the longitudinal axis of the companion spoke 28 and toward a line at right angles thereto passing through the axis of the shaft 13. In relatively spaced relation to the bearing portion 34, the web portion 35 terminates in a flange 36 secured to a bar 37 which is in turn made fast to a sweep blade 38. The sweep blade is generally rectangular in shape and has a leading edge 39 and a trailing edge 41, and may have, as indicated, a swept back formation placing one end of the trailing edge 41 closer to a line drawn through the axis of the shaft 13 than the corresponding end of the leading edge 39. The latter is bent upward slightly out of the plane of the body proper of the sweep blade. Immediately back up of such upturned portion is fastened the bar 37 which extends over a substantial part of the width of the blade in parallel, comparatively adjacent relation to the leading edge 39. The construction and arrangement of parts provides for a substantially rearward extension of the blade 38 beneath the attachment member 33 in such wise as to place the mounting bolt 31 and bearing portion 34 in relatively elevated relation to the sweep blade and in a location substantially parallel to the trailing edge of the blade and closer to such trailing edge than to the leading edge.

Also extending from the bearing portion 34 of the attachment member 33, in parallel relation to the web portion 35, is a lever arm 42. The outer free end of the lever arm 42 terminates substantially in line with the flange 36 and bar 37 and is received in a depending bifurcated portion 43' of a spider 43, to which bifurcated portion the lever is pivotally connected.

The spider 43 is mounted upon the shaft 13 for freedom of rotary and vertical sliding motion and is formed with a plurality of the bifurcated portions 43', one for each sweep blade assembly. The spider thus establishes a common connection between the several sweep blade assemblies and it will be understood that a vertical raising and lowering of the spider upon the shaft 13 will result in rocking movements of the lever arms 42 and thereby a tilting of the sweep blades 38 about their respective bolts 31. Also slidably mounted upon the shaft 13 is a sleeve 44 having a threaded lower end received in and secured to the spider 43. A set screw 45 may be used as indicated further to hold the spider and sleeve 44 from relative rotary motion. At the opposite or upper end of the sleeve 44 is a flange 46 and in immediately underlying relation to the flange 46 there is mounted on sleeve 44 a thrust bearing 47. A substantially U-shaped lift arm 48 is in embracing relation to the sleeve 44 and bearing 47 thereon, and carries studs 49 and 51 which underlie the bearing 47. On one side of the shaft 13 and sleeve-spider assembly thereon the lifting arm 48 is pivotally connected to a bracket 52 dependent from the gear box 12. On the other side of the shaft 13 the lift arm terminates in a finger 53 pivotally connected to an attachment clevis 54 on one end of the core 55 of a Bowden-wire or like flexible cable 56. The cable 56 is attached by a bracket 57 to the gear box 12 and by another bracket 58 to the stationary part 15 of the handle 14. Projecting beyond the bracket 58, the core 55 of the cable has attached thereto a hand grip or finger grip portion 59 accessible to the hand of the operator in order that it may be drawn upward or lifted to effect a corresponding lifting motion of the arm 48 about the bracket 52. Such a lifting motion of the arm 48 is effective through the studs 49 and 51 to raise the sleeve 44 and thereby the spider 43. As a result, the several attachment means 33 are rocked in a clockwise direction (Fig. 2) about their mounting bolts 31 in a direction to tilt the several blades 38, or more particularly to raise the leading edges 39 thereof. Differing extents

of pulling motion upon the handle grip 59 will, of course, effect different degrees of elevation of the leading edges of the sweep blades. The lift mechanism may be locked in such position by rotating the handle 59 approximately 90° and releasing it whereupon it will be held in the selected position of adjustment until it is desired again to change the blade adjustment.

To effect a lowering of the leading edges of the sweep blades, the handle grip 59 is released from its latched position and permitted to be drawn downward within the cable 56 by the force of gravity acting upon the troweling machine. When the desired lowered position has been achieved, the handle grip is again locked and the parts so held in adjusted position.

The construction and arrangement of parts is such as substantially to reduce the force required for an upward tilting movement of the troweling blades. The relatively long lever arms 42 multiply the lifting force applied to the spider 43 with the result that a multiplied torque is applied to the attachment means 33 in a direction to lift the sweep blades 38. The relatively off set mounting of the pivot for the blade, as represented by the bearing portion 34, with respect to the place of attachment of the blade, as represented by the flange 36, also is such as to provide for a greater angle of movement of the leading edge of the blade than that which takes place at the trailing edge thereof. The sweep blade thus in effect merely pivots about the trailing edge in response to the lifting action as applied to the handle grip 59. Further, the arrangement and spaced location of parts as described imparts a greater flexibility to the blade useful in achieving a live springing action of the blade upon the work surface and useful also to absorb some of the pulling forces applied through the handle grip 59 whereby to avoid having to apply these forces in a manner to lift the entire machine.

In the matter of leverage, in one working embodiment of the invention, the leverage provided by the lever arms 42 is approximately 2.7 to 1 while the advantage gained through the operator applied leverage as attained through the lifting arm 48 is approximately 4.2 to 1. The total advantage in leverage is approximately 11.4 to 1. Calculated against the weight of the machine in connection with which the adjusting mechanism is used, a machine weighing approximately 70 pounds, the leverage enables lifting of the sweep blades with the relatively light pull of 6.2 pounds, friction losses being neglected.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. A troweling or like machine including a rotary drive shaft, a circumferentially spaced series of bearings connected to said shaft for rotation therewith each projecting at right angles to a line radial to said shaft, a plate device pivotally supported on each of said bearings to one end to project at generally right angles thereto and inwardly toward said shaft, blade means attached to each of said plate devices at a line spaced from and generally parallel to its associated bearing, a lever arm connected with each of said plate devices for movement therewith about its bearing and extending generally perpendicular to its respective bearing and extending toward its

line of attachment to a blade means, and sleeve means vertically adjustable on said shaft connected to said lever arms in pivotal relation adjacent said lines of attachment of said devices to their connected blade means and means for vertically adjusting said sleeve means on said shaft for tilting said blades about their bearings.

2. Apparatus for troweling or the like including drive means having a vertically depending drive shaft, a support element fixed to said drive shaft, bearing means fixed to the periphery of said support element each projecting at generally right angles to a line radial to said shaft, a spider mounted on said shaft in adjacent relation to said support element to have a freedom of vertical and rotary movement with respect to said shaft, a web member with one end rotatably mounted on each of said bearing means and having its other end project inwardly toward said shaft, a sweep blade secured to said other end of each web member adjacent and parallel to

its leading edge, said leading edge being parallel to said bearing, a lever means connected for rotation with each web member having a projected extremity pivotally connected to said spider, means for vertically moving said spider to produce a mutual tilting of said sweep blades.
